UNITED STATES PATENT OFFICE.

DAVID H. PERKINS, OF MANSFIELD, MASSACHUSETTS, ASSIGNOR TO THE
D. F. BRIGGS COMPANY, OF ATTLEBORO, MASSACHUSETTS.

CLASP FOR JEWELRY.

SPECIFICATION forming part of Letters Patent No. 776,256, dated November 29, 1904.

Application filed June 15, 1903. Serial No. 161,412. (No model.)

To all whom it may concern:

Be it known that I, DAVID H. PERKINS, a citizen of the United States, residing at Mansfield, in the county of Bristol and State of Massachusetts, have invented a new and useful Improvement in Clasps for Jewelry, of which the following is a specification.

This invention has reference to an improvement in clasps used to clasp or fasten necklaces, bracelets, or similar articles, and more particularly to an improvement in a clasp constructed to form a combined clasp and locket.

The object of my invention is to construct a combined clasp and locket in the form of a padlock.

My invention consists in the peculiar and novel construction of a clasp having the form of a padlock, the hasp of the padlock forming the means of clasping or fastening a necklace or similar article, and the body of the padlock forming a locket having a hinge and means for securing the clasp and locket in the closed position, as will be more fully set forth hereinafter.

Figure 1 represents a front view of my improved combined clasp and locket constructed in the form of a padlock clasping or fastening the ends of a chain (shown in broken lines) forming part of a necklace or bracelet. Fig. 2 is an inside view of the part forming the front of the clasp and locket. Fig. 3 is a side view of the hasp, the shank of which forms the pivot-pin for the hinge of the clasp. Fig. 4 is an inside view of the part forming the back of the clasp and locket. Fig. 5 is an enlarged view of the clasp in the open position looking at the inside and showing the back in section; and Fig. 6 is a view looking at the hasp end of the clasp, showing the clasp in the open position and the back partly in section.

In the drawings, *a* represents the front, *b* the back, and *c* the hasp, of my improved combined clasp and locket constructed in the form of a padlock. The front *a* has the upwardly-extending wings *a'* *a''*, the raised circular lip *a''*, the tubular sleeve *a''*, the fastening-pin *a''*, and the picture-retaining ring *a''*. The back *b* has the upwardly-extending wings *b'* *b''*, the

raised circular lip *b''*, the tubular sleeve *b''*, the fastening-aperture *b''*, and the picture-retaining ring *b''*, and the hasp *c* has the free end *c'* and the shank *c''* reduced in size to form the pivot-pin of the hinge when inserted through the tubular sleeves *a''* and *b''* and secured by enlarging its end.

When the parts of the clasp are assembled, the hasp *c*, in connection with the wings *a'* and *b'*, form the clasp and the front *a* and the back *b* form the locket. The fastening-pin *a''* on the front coinciding with the fastening-aperture *b''* in the back holds the clasp and locket in the closed position by friction. The picture-retaining rings *a''* and *b''* are forced into the circular lips *a''* and *b''*. These rings are constructed with inwardly-turned flanges to limit their inward movement and to form spaces in the front and back for the insertion of thin disks of transparent celluloid and the picture or similar articles.

In the use of my combined clasp and locket the hasp *c* is free to move sidewise when the clasp is open. The free end *c'* of the hasp is inserted through the ends of the necklace or similar article and the clasp is closed and secured in the closed position by the fastening-pin *a''*. The closing of the clasp brings the hasp *c* between the wings *a'* and *b'*, thus preventing its removal from the necklace or similar article without opening the clasp.

It is evident that any well-known form of fastening device for securing the clasp in its closed position could be used and that the form of the clasp could be varied without materially affecting the spirit of my invention.

Having thus described my invention, I claim as new and desire to secure by Letters Patent—

1. In a combined clasp and locket, the combination with a hinged two-part hollow body forming the locket, of an inverted-U-shaped pivoted arm forming a continuation of the pivot-pin and forming the hasp, and means for securing the two parts of the locket in the closed position, as described.

2. A combined clasp and locket, consisting of a hinged two-part hollow body with picture-retaining rings forming the locket, an inverted-U-shaped pivoted arm formed inte-

gral with the pivot-pin of the hinge and forming the hasp, and means for securing the locket and the hasp in the closed position, as described.

5 3. In a combined clasp and locket, the combination with the front a having the wings a' a' , the raised circular lip a^2 , the tubular sleeve a^3 , the fastening-pin a^4 , and the picture-retaining ring a^5 , the back b having the wings b' b' , the raised circular lip b^2 , the tubular sleeve b^3 , the fastening-aperture b^4 , and the

picture-retaining ring b^5 , and the hasp c having the free end c' and the shank c^2 forming the pivot-pin for the tubular sleeve a^3 and b^3 , all for the purpose as described. 15

In testimony whereof I have signed my name to this specification in the presence of two subscribing witnesses.

DAVID H. PERKINS.
